UNITED STATES PATENT OFFICE.

DANIEL J. McCARTHY, OF ELGIN, ILLINOIS, ASSIGNOR TO CHICAGO RAILWAY SIGNAL AND SUPPLY COMPANY, OF CARPENTERSVILLE, ILLINOIS, A CORPORATION OF ILLINOIS.

ADJUSTABLE ENGAGING DEVICE FOR MACHINE ELEMENTS.

1,333,500.

Specification of Letters Patent.

Patented Mar. 9, 1920.

Application filed August 24, 1918. Serial No. 251,250.

To all whom it may concern:

Be it known that I, DANIEL J. McCARTHY, a citizen of the United States, residing at Elgin, in the county of Kane and State of Illinois, have invented certain new and useful Improvements in Adjustable Engaging Devices for Machine Elements, of which the following is a specification.

My invention relates to a device for providing an adjustable engagement between two machine elements capable of angular or rotational movement one with respect to the other, such, for example, as a shaft and cam mounted thereon; and a primary object of the invention is to provide a device for use in this or analogous situations which will be simple and inexpensive to manufacture and which will afford convenient means for effecting the engagement of one element with the other which will be positive and reliable and capable of minute adjustment.

A more specific object of the invention is to provide electric switches of certain types with means whereby the timing of the movements of the current controlling contacts, or switch elements, may be readily, accurately and conveniently adjusted.

The invention consists in the new and improved constructions, arrangements and devices to be hereinafter described and claimed for carrying out the above stated objects and such other incidental objects as will appear from the following description of certain preferred embodiments of the invention.

These embodiments of the invention are illustrated in the accompanying drawings, wherein—

40 Fig. 1 is a sectional view of an electric switch which, in its general construction, is of familiar type but contains the improvement which is the subject matter of my invention.

45 Fig. 2 is a sectional plan on line 2—2 of Fig. 1.

Fig. 3 is a detail sectional plan on a larger scale taken on line 3—3 of Fig. 1.

Fig. 4 is a sectional view on line 4—4 of Fig. 3.

Figs. 5 and 6 are fragmentary views on the same section line as Fig. 4 to illustrate different positions of the parts of the adjusting device, and

Fig. 7 is a view, in elevation, with the shaft in section, of a modified form of electric switch embodying the principle of my invention applied in a somewhat different way.

Like characters of reference designate like parts in the several figures of the drawings.

Referring first to Figs. 1 to 6 inclusive, 10 is a casing for the switch mechanism provided with a cover 11. Mounted on a web 12 of the casing is a block of insulating material 13 to which is secured the spring contacts 14, 15 and 16 having binding posts 17, 18, 19, respectively, contact 16 being supported from the block 13 by a bracket 20 so that it is arranged opposite contact spring 70 15. 21 is a rocker arm carried on a shaft 22 and provided at opposite ends with rollers 23 adapted to bear against a cam 24 which is associated with a shaft 25. The rocker arm is connected by link 26 with a 75 forked member 27 on the contact spring 14. The rotation of shaft 25 and cam 24 move the spring 14 out of contact with spring 15 and into contact with spring 16, and vice versa.

80 The switch mechanism as thus far described is of known construction. My invention relates to an arrangement for adjusting the cam 24 with respect to shaft 25 so that the movement of the switch will be 85 properly timed. This arrangement is preferably as follows: Between shaft 25 and cam 24 is a disk 28 having a hub 29 rigidly secured to the shaft by means of a key 30, or other suitable means. The disk 28 is formed 90 on its periphery with a pair of alined recesses 31 which taper in depth toward each other and meet at their shallow ends. The cam 24 fits the disk 28 somewhat closely but freely enough to allow the rotation of the 95 cam on the disk. In each of the recesses 31 is arranged a revoluble clutch member, preferably a roller 32, which is normally pressed toward the shallow end of the recess by a coiled spring 33 seated in a bracket 34 100 formed in the disk. On one face of disk 28 is arranged a circular plate 35 formed with arcuate slots 36 through which extend screws 37 threaded into the disk 28, the heads 38 of which bear against the plate 35 and clamp 105 the same to the disk 28. When the screws 37 are loosened the plate may be rotated to the extent of the length of slots 36. For ro-

tating the plate it is provided with a lug 39. The plate 35 preferably overlaps cam 24 on one side. The disk 28 is formed with a flange 40 which overlaps the cam on the other side (Fig. 3). Secured to the plate 35 is a stud 41 which extends into slots 31, 31 at their intersection in position to engage one or other of the clutch rollers 32 when the plate is rotated. By this arrangement the cam may be adjusted conveniently with accuracy and minuteness in either direction. If the cam is to be rotated to the right (Fig. 5) the plate 35 is turned to the left which brings stud 41 against the left hand roller 15 of the pair forcing this roller into the deep end of its recess. The cam may then be moved in the direction indicated by the arrow in this figure because its movement in this direction causes the other roller, the right hand one of the pair, to move back toward the deep end of its recess. If the adjustment is to be made in the opposite direction the parts are reversely moved, as shown in Fig. 6. When the proper adjustment has been 20 made the plate 35 is turned back to its initial position with screws 37 at the middle of slots 36 and the screws are tightened. As soon as the clutch roller engaged by the stud is released by the movement of the stud to 25 its intermediate position, the spring back of the roller forces it toward the shallow end of its recess so that no movement or rotation in either direction of the cam with respect to disk 28 and shaft 25 is possible. That is to say, in accordance with the arrangement 30 described one of the clutch members will oppose relative movement in one direction between the parts engaged while the other will oppose such movement in the opposite direction. By turning the plate in one 35 direction one of the clutch members is put out of operation while by rotating the plate reversely the other clutch member is made inoperative. Thus the cam may be turned in either direction so as to obtain conveniently 40 an accurate adjustment thereof with respect to the shaft 25 by which the switch mechanism is actuated. I have referred to only one pair of clutch rollers 32. Preferably, 45 however, there are several pairs of these rollers arranged in a corresponding manner between the disk 28 and cam 24, the plate 35 being provided, of course, with a corresponding number of studs 41. The object of 50 multiplying the clutch rollers is to insure a positive engagement of the cam and disk.

In Fig. 7 I have shown a modified switch or circuit making and breaking mechanism employing the same principle of construction. The circuit making and breaking elements comprise a pair of spring contacts 42 and, arranged between the same, a revoluble annular contact member 43 which is cut away as indicated at 44. The revoluble contact, which corresponds generally to the

cam 24 of the other form of the invention, is arranged at the periphery of a disk 45 having a square opening 46 at the center for mounting on the squared portion 47 of the actuating shaft of the mechanism, the disk and shaft being insulated by the insulating material 48. The disk 45 is formed with recesses 49 in which are arranged spring pressed rollers 50 which may be forced to inoperative position by means of the stud 51 on the annular plate 52 which is engaged with disk 45 by means of screws 37 which extend into the disk 45 through arcuate slots 54 formed in plate 52; the construction being substantially the same in the respects last noted as that previously described.

I claim:

1. The combination of two machine elements, one of which is capable of rotation on the other and which are formed to provide recesses between the elements which taper in depth toward each other, a revoluble clutch member in each of said recesses for normally preventing relative rotation in either direction, and means for forcing one of said members into the deep end of its recess to permit the adjustment rotationally of one element on the other. 85

2. The combination of two machine elements, one of which is capable of rotation on the other and which are formed to provide recesses between the elements which taper in depth toward each other, a revoluble clutch member in each of said recesses, springs which press said members toward the shallow ends of their recesses, and means for forcing one of said members into the deep end of its recess to permit the adjustment rotationally of one of said elements on the other. 95

3. The combination of two machine elements, one of which is capable of rotation on the other and which are formed to provide recesses between the elements which taper in depth toward each other, a revoluble clutch member in each of said recesses, springs which press said members toward the shallow ends of their recesses, and means adapted to engage either of said clutch members and force the same into the deep end of its recess, whereby one element may be adjusted rotationally in either direction on the other. 105

4. The combination of two machine elements, one of which is capable of rotation on the other and which are formed to provide recesses between the elements which taper in depth and communicate with each other at their shallow ends, revoluble clutch members in said recesses, springs which press said members toward the shallow ends of their recesses, and a device rotatably engaged with one of said elements having a projection which extends into said recesses at their intersection, by the rotation of 110 125 130

which device in one direction or the other the projection thereon forces one of said clutch members into the deep end of its recess.

5. The combination of two machine elements, one of which is capable of rotation on the other and which are formed to provide recesses between the elements which taper in depth and communicate with each 10 other at their shallow ends, revoluble clutch members in said recesses, springs which press said members toward the shallow ends of their recesses, a device rotatably engaged with one of said elements having a projection which extends into said recesses at their intersection, by the rotation of which device in one direction or the other the projection thereon forces one of said clutch members into the deep end of its recess, and means 15 for fixing said device to the element with which it is engaged.

6. The combination of a disk having in its periphery a pair of alined recesses tapering in depth and communicating with each 20 other at their shallow ends, an annular element surrounding said disk, a pair of rollers arranged in said recesses, respectively, springs which press said rollers toward the shallow ends of the recesses, and a plate ro-

tatably arranged with respect to said disk 30 having a stud which projects into said recesses at their intersection adapted, when the plate is rotated, to engage one or other of said rollers and force the same into the deep end of its recess.

7. The combination of a disk having in its periphery a pair of alined recesses tapering in depth and communicating with each other at their shallow ends, an annular element surrounding said disk, a pair of rollers 40 arranged in said recesses, respectively, springs which press said rollers toward the shallow ends of the recesses, a plate rotatably arranged with respect to said disk having a stud which projects into said recesses 45 at their intersection adapted, when the plate is rotated, to engage one or other of said rollers and force the same into the deep end of its recess, said plate being formed with arcuate slots, and clamping devices 50 extending into said slots for clamping the plate to said disk.

June 26, 1918.
